ELECTRIC SWITCH

Frank R. Moore, Upper Darby, Pa., assignor, by
mesne assignments, to Harvey C. Bridgers, Blue
Ridge Summit, Pa.

Application October 12, 1933, Serial No. 693,367

2 Claims. (CL. 200—83)

This invention relates to pressure operated electric switches and its object is to provide a simplified pressure operated switch in which the contact making element is operated by a single 5 spring which is arranged so as to produce a quick snap action.

A further general object is to provide a pressure operated switch adapted for any and all uses for making and breaking a circuit in response to 10 variation in some pressure condition in a system with which the switch is associated.

Referring to the accompanying drawings, which are made a part hereof and on which similar reference characters indicate similar parts,

15 Figure 1 is a side elevation partly in section of my switch,

Figure 2, a plan view of the switch with the cover of a casing removed,

Figure 3, a section on line 3—3 of Figure 1,
20 Figure 4, a section on line 4—4 of Figure 1, and
Figure 5, a section on line 5—5 of Figure 4.

In the drawings numeral 10 indicates the base 25 of the switch having an upright portion 11 in which is mounted a cylinder 12 which is secured in the portion 11 by means of the screw 13. A diaphragm 14 is secured against a shoulder 15 in an enlarged end of the cylinder 12 by means of a cap 16 which is threaded into the enlarged end of the cylinder so as to secure the diaphragm in 30 position. A chamber 17 is provided between the cap and the diaphragm and an inlet pipe 18 is threaded into the cap. A suitable air conduit or other fluid conduit, not shown, may be attached to the end of the pipe 18 for supplying fluid under 35 pressure to the chamber 17.

A rod 19 is suitably secured to the diaphragm 17 as by means of washers or nuts 20. A compression spring 21 is positioned within the cylinder 12 and is confined between washers 22 and 23.

40 A plug 24 is threaded into the inner end of the cylinder 12 and engages the washer 23 and serves to tension the spring 21. The inner end of the rod 19 is provided with spaced collars 25 and 26, the latter of which may be adjusted axially of the 45 rod 19 and secured in adjusted position by means of a set screw 26. A lever 27 is fixed upon a pin 28 which is journaled in a bushing 29 in a standard 30 which standard is secured to the base 10. The lower end of the lever 27 carries a pin 31

50 which is positioned between and engaged by the collars 25 and 26. The upper end of the lever 27 is forked as shown at 32 and between these forks is positioned a pin 33 on the lower end of a lever 34 which lever is pivoted at 35 to the post 30. The upper end of the lever 34 carries a pair

of contact pins 36 which may be connected by a bar 37. The lever 34 is preferably made of insulating material but may be made of conductive material in which latter case contacts 36 will be insulated from the lever. Mounted upon or made integral with the post 30 is a block 38 which also carries contact pins 39. Binding posts 40 and 41 are connected to these contact pins and wires 42 and 43 are connected respectively to the binding posts 40 and 41. The shaft 28 upon which the lever 27 is mounted extends through the post 30 and carries an arm 44 rigidly secured on its opposite end to which arm is fixed a split pin 45. A spring 46 is secured by means of screws 47 and locks 48 to post 30 and is positioned in the slit in the pin 45. This spring is slightly bulged so as to provide a snap action as the lever 47 is rocked back and forth by means of the piston 19. A cover 49 may be secured upon the base and held in position by a nut 50.

In operation pressure fluid is supplied to the chamber 17 through the tube 18. When this pressure reaches a predetermined point the spring 21 is compressed and the rod 19 moved to the left to rock the lever 27 clockwise of the position shown in Figure 1. When the lever 27 has been rocked clockwise sufficiently to buckle the spring 46 this spring snaps to the opposite extreme and causes the upper end of the lever 27, by means of the pin 33, to rock the lever 34 counterclockwise, when viewed in the position shown in Figure 1, to separate contacts 36 and 37 and break circuit through wires 42 and 43.

While in the embodiment of the invention as shown pressure fluid is used to operate the switch, 35 the invention is not limited in its use in this respect. The rod 19 which is operatively connected to the switch may be operated in any manner such for example as a push button which operates directly or indirectly on the rod in opposition to the spring 21 or even in the absence of the spring 21 in which case it operates simply to snap the flat spring 46 to each limit of movement. Of course after the spring 46 is moved a predetermined distance it will buckle and move itself 40 sufficiently far to open or close the main switch. It should be perfectly obvious therefore that the spring may be caused to be buckled by pressure fluid or by any other pressure means or mechanical means by which it is caused to move a certain distance after which it will buckle to move 45 itself to the limit in that direction.

While double contacts have been shown it is 50 obvious that the switch could be made with only 55

single contacts with one of the wires 42 or 43 attached to the contact 36.

It will be obvious to those skilled in the art that various changes may be made in my device without departing from the spirit of the invention and therefore I do not limit myself to what is shown in the drawings and described in the specification, but only as indicated by the appended claims.

10 Having thus fully described my said invention, what I claim as new and desire to secure by Letters Patent, is:

1. An electric switch comprising a base, a cylinder mounted on said base, a diaphragm positioned within said cylinder, means for supplying pressure fluid to said cylinder and against one side of said diaphragm, a spring acting against said diaphragm and in opposition to said pressure, a rod secured to said diaphragm and extending 15 out through said cylinder, a pair of spaced collars on said rod, a lever pivotally mounted on said base and having an element engageable by said collars to rock said lever, a shaft fixed to said lever and forming the fulcrum therefor, an arm fixed to said shaft, said arm carrying a split pin adjacent its outer end, a flat spring fixed at each end and

passing through the split in the said pin, a second lever pivotally mounted on said base, said lever having an element thereon engageable by said first named lever in each direction of movement of said first lever, and having a contact element thereon, a fixed contact element on said base, flexing of the said diaphragm causing a snap action movement of said contacts together and apart as the pressure of said pressure fluid varies above and below a predetermined degree. 10

2. A switch comprising a support having a fixed contact element mounted thereon, a second contact element movable into and out of engagement with the fixed contact, a lever operatively connected to said movable contact, a shaft supporting said lever, an arm on said shaft, a split pin on said arm, a spring extending through said pin and secured at each end in fixed position on said support, and pressure fluid means for rocking said lever, and thereby biasing said spring first 15 in one direction to open said contacts and then in the other direction to close the contacts, said spring operating to cause a snap action movement of said movable contact after the lever has been rocked a predetermined distance. 20
